UNITED STATES PATENT OFFICE.

EDWIN L. EDES, OF PLYMOUTH, MASSACHUSETTS.

DESIGN FOR AN ORNAMENTAL BOX.

SPECIFICATION forming part of Design No. 23,102, dated March 6, 1894.

Application filed October 18, 1893. Serial No. 488,545. Term of patent 14 years.

To all whom it may concern:

Be it known that I, EDWIN L. EDES, a citizen of the United States, residing in Plymouth, in the county of Plymouth and State of Massachusetts, have invented and produced a new and original Design for Ornamental Boxes, of which the following is a full, clear, and exact description, reference being had to the accompanying drawings, making a part of this specification.

This design relates to a box for holding light and trifling articles such as pens, pins, &c.

In the drawings Figure 1, is a side view, Fig. 2 a top view and Fig. 3 an end view of a box or receptacle provided with the configuration and characteristics which together, constitute or comprise my said design. Fig. 4 is a diagram on a greatly enlarged scale intended to make more clear of comprehension the character of the cross-hatched surface which enters into my said design as an element thereof and which is shown in about the intended or actual proportions in Figs. 1 to 3 inclusive.

The body, A., of the box is of oblong shape as shown in Figs. 1 and 2, and with rounded ends as more plainly represented in said Fig. 2. One end of this body is prolonged upwardly to present the appearance of a hood, B., which is rounded at its back and sides but at the front, a, is arched as shown at the outline a' of Fig. 3. Horizontally along the back and sides of this part B. are smooth convex horizontal beads or moldings, b, and along the sides and ends, at top and bottom of the part A., are similar smooth and convex moldings indicated by the reference letter c; which are continued around the ends of the body A. Above the upper moldings c, the edge of the

body, A. somewhat overhangs the surface below as shown at d. in Fig. 1.

Aside from the beads and moldings b and c, the external surface of the parts A. and B. (excepting of course the bottom of the former) is formed with a cross-hatching of thin sharply defined raised lines or minute ridges, e, which cross each other at right angles or substantially so as shown in each of the several figures, with cavities, e', as shown on a considerably enlarged scale in Fig. 4, in the spaces between them. These raised and accentuated ridges with the cavities, e', between them (represented at about the actual size in Figs. 1 to 3 inclusive) present to the eye of the beholder a symmetrically roughened surface; this symmetrically roughened surface being common to both the parts A. and B. affords an appearance of unity to the whole exterior of the box, which is heightened by the correspondence of the beads or moldings, b, with the beads or moldings, c, the juxtaposition of the described symmetrically roughened surface with the smoother surfaces of the aforesaid beads or moldings affords a pleasing contrast and the oblong shape of the part A. in conjunction with the rounded hood-like configuration of the part B. and the rounded contour of the ends of the latter afford a fanciful and at the same time symmetrical contour to the whole.

What I claim as my invention is—

The design for an ornamental box or receptacle, substantially as herein described.

EDWIN L. EDES.
